UNITED STATES PATENT OFFICE.

HENRY M. WALLIS, OF RACINE, WISCONSIN, ASSIGNOR TO THE MITCHELL & LEWIS COMPANY, (LIMITED,) OF SAME PLACE.

ROAD-CART.

SPECIFICATION forming part of Letters Patent No. 299,441, dated May 27, 1884.

Application filed August 27, 1883. (No model.)

To all whom it may concern:

Be it known that I, HENRY M. WALLIS, of Racine, in the county of Racine, and in the State of Wisconsin, have invented certain new and useful Improvements in Road-Carts; and I do hereby declare that the following is a full, clear, and exact description thereof.

My invention relates to improvements in thill-adjusters for two-wheeled vehicles, and it will be fully described hereinafter.

In the drawings, Figure 1 is an elevation of the thill-adjuster; and Fig. 2 is a vertical section through near center, showing attachment of adjuster-bar and brace.

15 A is the adjuster-bar having both ends bent up, the rear end being enlarged and shaped so as to be conveniently bolted on axle, which it firmly grasps, while the other end is provided with a thread to screw in lower head of 20 turn-buckle C.

B is an S-shaped hanger having a thread cut in its lower straight end, to screw in upper head of said turn-buckle, and its opposite end held tight by a bolt in center of cross-bar a.

25 D' is a rod firmly secured, in any suitable manner, both to the axle and to the adjuster-bar A, to strengthen same.

E is the brace-rod suitably attached to hangers D on axle b and shafts, to strengthen said 30 shafts and secure the full action of the thill-adjuster. The adjusting of the vehicle-body to a level position, whether a small or large

sized horse be hitched to the cart, is effected by a few turns of the buckle C either right or left, as needed.

It will be seen that the bar A not only serves as an adjustable support for the shafts, but it also serves to greatly strengthen the gear of the cart.

Having thus described my invention, what I claim as new and useful, and desire to secure by Letters Patent, is—

1. In a thill-adjuster, a curved bar secured and braced to the axle, and having its free end bent up and threaded, a bent hanger projecting from cross-bar, and having its threaded end in line with that of the first-mentioned bar, and a turn-buckle, which connects the ends of the two bars, substantially as described, and for the purpose set forth.

2. In a thill-adjuster, the combination, with the shafts and axle, of the curved adjuster-bar A and the curved hanger B, arranged as shown, and connected by turn-buckle, and the hanger D, having brace E, connecting to the shafts, substantially as shown and described.

In testimony that I claim the foregoing I have hereunto set my hand, on this 28th day of July, 1883, in the presence of two witnesses.

HENRY M. WALLIS.
